LAUNDRY MACHINE

Ralph Apicella, Jersey City, N. J., assignor to
 Apex Machinery Co., Newark, N. J., a corpora-
 tion of New Jersey

Application August 19, 1940, Serial No. 353,207

1 Claim. (Cl. 68—140)

This invention relates to a laundry machine and, more particularly, to a laundry machine having a cylindrical tub portion in which is revolvably mounted a clothes container.

In machines of this general type, prior to the invention of this application, the clothes container was rotated by means of a direct gear drive which necessitated the exact alignment of the driven gear, which was generally a large one, was difficult and expensive to replace after becoming worn. In prior machines, it was also difficult to gain access to the clothes container or remove the same from the tub portion.

It is an object of the present invention to provide a laundry machine in which easy access to the clothes container may be had.

Another object of this invention is to provide a laundry machine in which the clothes container may easily be removed from the tub portion.

A still further object of the present invention is to provide a laundry machine in which the driven gear on the clothes container shaft is eliminated.

The above and other objects of the present invention will become apparent in the course of the following specification.

The above and other objects of the present invention may be realized by providing a substantially cylindrical tub portion formed of a plurality of wood staves mounted on semi-circular supports and enclosed by end pieces. The upper section of the forward part of the tub portion is open.

The tub portion is formed in two substantially equal sections one separable from the other, the upper and lower portions normally being held together by means of removable end clamps.

Rotatably mounted within the tub portion in nested relation thereto is a cylindrical clothes container having a hinged door therein said clothes container being mounted on a shaft extending through the end pieces of the tub portion, the shaft being mounted in bearings on the end frame pieces.

Sprocket wheels are mounted on the shaft adjacent both ends of the clothes container and on the inner side of the tub end pieces. Drive chains connect the sprocket wheels to sprocket wheels mounted on a drive shaft supported from extensions on the end frame pieces. The drive shaft may be driven by means of a belt connecting it to a power source.

The invention will appear more clearly from the following detailed description when taken

in connection with the accompanying drawings, showing by way of example a preferred embodiment of this invention.

In the drawings:

5 Figure 1 is an end elevational view partly broken away of the device of this invention.

Figure 2 is a front elevational view taken on the line 2—2 of Figure 1;

10 Figure 3 is a longitudinal sectional view taken on the line 3—3 of Figure 1; and

Figure 4 is a transverse sectional view taken on the line 4—4 of Figure 2.

Like numerals refer to like parts throughout the several views.

The device of this invention comprises a tub portion 10 having an upper section 11 and a lower section 12, one separable from the other.

20 The lower section 12 is substantially semi-cylindrical in shape and is composed of a plurality of wood staves 13 and is enclosed by opposite end pieces 14 and 15. The lower section 12 is supported by frame pieces 16, 17 and 18, the inner surface of which are of semi-circular shape to conform to the contour of the outside surface of the lower section 12 of the tub portion. The frame pieces 16, 17 and 18 may be anchored to the floor by any desirable means and may be braced by suitable cross pieces 19 and 20.

25 30 The upper section 11 of the tub portion comprises two semi-circular end pieces 21 and 22 at opposite ends thereof, the back being formed of a plurality of wood staves 23, the front thereof being open.

35 The upper section 11 is held in relation to the lower section 12 on one end by means of a semi-circular end clamp 24 formed of two parts 25 and 26, the part 25 being removably fastened to the front of the frame piece 18 by a bolt 27

40 and the part 26 being fastened to the rear of the frame piece 18 by a bolt 28. The two parts are fastened together by a bolt 29. The opposite end of the upper section 11 is held in relation to the lower section by a similar clamp 30 likewise formed of two parts 31 and 32, the part 31 being removably fastened to the front of the frame piece 16 by a bolt 33 and the part 32 fastened to the rear of the frame piece 16 by a bolt 34. The two parts 31 and 32 of the clamp 30 are

45 50 55 fastened together by a bolt 35.

A clothes container 36, cylindrical in shape and formed of a plurality of wood staves 37 fastened to opposite end plates 38 and 39, is revolvably mounted within the tub 10 in nested relation thereto. A shaft 40 on the end plate 38

and a shaft 41 on the end plate 39 extend through the adjacent ends of the tub 10, the shaft 40 being adapted to rotate in the pillow block 42 on the frame piece 16 and the shaft 41 to rotate in the pillow block 43 on the frame piece 18 and act as an axis upon which the clothes container rotates. The pillow blocks 42 and 43 may have ball bearings therein, as illustrated, or any other type of bearing.

Keyed on the shaft 40 between the end plate 10 38 and the end piece 14 of the tub 10 is a sprocket wheel 44. A sprocket wheel 45 is keyed to the shaft 41 between the end plate 39 and the end piece 15.

The sprocket wheel 44 is connected by means of a driving chain 46, passing through a slot 46a in the upper section 11, to a sprocket wheel 47 fixedly mounted on a drive shaft 48. The drive shaft 48 extends longitudinally of the machine and is rotatably mounted at one end in a bearing 49 on an extension 50 on the frame piece 16, the opposite end being rotatably mounted in a bearing 51 on an extension 52 on the frame piece 18.

The sprocket wheel 45 by means of a drive chain 53 which passes through a slot 54 in the upper section 11 of the tub portion 10 is connected to a sprocket wheel 55 fixedly mounted on the shaft 48.

The shaft 48 is driven by means of a belt 56 passing over a pulley 57 on the shaft 48. The belt 56 may be connected directly to a power source or connected to a reversing mechanism of any well known construction, not shown, which will rotate the clothes container 36 a predetermined number of times in one direction and then a predetermined number of times in the opposite direction.

The clothes container 36 has a door 58 extending lengthwise thereof, the door being hinged at 59 and 60. Each hinge has a locking mechanism 61 to hold the door closed when the container is being rotated. The door 58 has a plurality of holes 62 bearing a staggered relation to one another. If desired the door 58 may be divided into a plurality of longitudinal sections, so that it will be necessary to raise only one section at a time, avoiding the difficulty of raising the weight of a door extending the entire length of the container 36.

In an aperture 63 in the bottom of the tub 10 is a drain plug 64. One end of a lever 65 is pivotally connected at 66 to the plug 64 and at 67 to a bracket 68 mounted on the bottom of the lower section 12 of the tub 10. The opposite end of the lever 65 is pivoted at 69 to a vertically extending lever 70 which is fastened to a handle 71 pivoted at 72 to the end piece 14. A spring 73 is attached to the handle 71 and end piece 14, the tension of the spring tending to pull the handle downwardly, holding the plug 64 in position in the aperture 63. The handle 71 is lifted upwardly to drain the tub 10.

In the operation of the laundry machine of this invention, clothes are placed within the clothes container 36 after raising the door 58. The door is then closed and locked by the locking mechanism 61, which consists of a headed pin 73 adapted to be passed through the clevis 74 and an aperture in the end of the hinge 60 and held by means of a thumb screw 75. Cleaning fluid, water or any other desired fluid, is contained within the clothes container 36. Power is applied to the shaft 48 through the belt 56 and pulley 57, rotating the shaft. Rotation of the

shaft 48 and sprocket wheels 47 and 55 causes rotation of the clothes container 36 through the drive chains 46 and 53 connected, respectively, to the sprocket 44 on the shaft 40 and the sprocket wheel 45 on the shaft 41.

It becomes necessary after use of a laundry machine for a period of time to have access to the clothes container or inner cylinder 36. With the present invention, it is merely necessary to remove the end clamp 24 by removing the bolts 27, 28 and 29, and the end clamp 30 by removing the bolts 33, 34 and 35. After the drive chains 46 and 53 have been disconnected, the top or upper section 11 may be lifted away from the bottom or lower section 12, giving access to the clothes container 36.

If it is desired to replace or for any other reason remove the clothes container from the tub 10, the tops of the pillow blocks 42 and 43 are removed after removing the bolts holding them to the frame pieces 16 and 18, respectively. The clothes container 36 may then be removed from the tub 10 by lifting the same upwardly and away from the said tub portion.

In the device of the present invention, driving gears on the clothes container 36 are dispensed with, these gears being costly and difficult to align with the gears driving them, which leads to great expense when replacing them after they become worn. It is also difficult to re-assemble the machine and align the gears on the clothes container with the gears driving them. The clothes container gears on present machines of this type are usually on the outside of the tub portion thereof where they constitute a danger to the operator of the machine, whereas in the device of the application, the sprocket wheel and driving chain are concealed behind the tub end pieces.

It is apparent that the specific illustrations shown have been given by way of illustration and not by way of limitation and that the structure above described is subject to a wide variation and modification without departing from the scope or intent of the invention, all of which variations and modifications are to be included within the scope of the present invention.

What is claimed is:

In a laundry machine, in combination with a rotary cylindrical clothes container and a substantially cylindrical tub portion enclosing said container, driven shafts carrying said container and rotatable therewith, said shafts extending through opposite ends of said tub portion, said tub portion being longer than said container, sprocket wheels keyed upon said shafts and situated at opposite ends of said container within said tub portion, frame pieces situated at opposite ends of said tub portion and supporting the same, means carried by said frame pieces for supporting said shafts at opposite ends thereof, each of said frame pieces comprising an extension member extending to one side and above said tub portion, bearings carried by said extension members and situated above said tub portion, a driving shaft having two ends carried by said bearings, sprocket wheels keyed upon said driving shaft, and endless chains extending from each of the sprocket wheels upon the driven shafts to a separate sprocket wheel upon the driving shaft, said chains extending through openings formed in said tub portion.
